UNITED STATES PATENT OFFICE.

JOHN M. YOUNG, OF SAN FRANCISCO, CALIFORNIA, ASSIGNOR TO AMERICAN CAN COMPANY, OF NEW YORK, N. Y., A CORPORATION OF NEW JERSEY.

FRICITION-TOP CAN.

1,091,612.

Specification of Letters Patent. Patented Mar. 31, 1914.

Application filed June 16, 1909. Serial No. 502,427.

To all whom it may concern:

Be it known that I, JOHN M. YOUNG, a citizen of the United States, residing in San Francisco, in the county of San Francisco 5 and State of California, have invented a new and useful Improvement in Friction-Top Cans, of which the following is a specification.

My invention relates to friction top cans. 10 The object of my invention is to provide a friction top can of a simple, efficient and durable construction, suitable for use for coffee, spices and other articles, and which at the same time will be incapable of being 15 opened without detection for refilling with spurious goods.

My invention consists in the means I employ to practically accomplish this object as herein shown and described, without increasing the number of the sheet metal parts 20 of the friction top. That is to say, it consists in connection with a can body, having an inturned flange at its upper end, of an annular top head fitting within the can 25 body and having a reversely folded rim embracing the inturned flange of the can body, a friction cover closing the opening in the annular top, and a safety seal, preferably of paste-board or paper, extending across the 30 friction cover and clamped between the annular top and its reversely folded rim which embraces the inturned flange of the can body and also serves as the fulcrum or pry-off rim for levering up the friction 35 cover. The removable friction cover and the external safety seal therefor are applied at the factory where the cans are manufactured, and the bottom head is not applied to the can body until after the can is filled 40 with coffee, spices or other articles to be sold in the cans, the bottom thus being preferably double seamed on the filled can.

My invention also consists in the novel construction of parts and devices and in the 45 novel combinations of parts and devices herein shown and described and more particularly specified in the claims.

In the accompanying drawing forming a part of this specification, Figure 1 is a central vertical section of a friction top can 50 provided with a safety seal embodying my invention. Fig. 2 is a plan view. Fig. 3 is a plan view, showing the can after the safety seal is removed. Fig. 4 is an enlarged partial sectional view and Fig. 5 is a

detail, partial sectional view showing the position of the parts before the external safety seal is permanently or irremovably secured to the can body and can head across the friction cover.

In the drawing, A represents the body of a friction top can, preferably having a lock side seam a, B the annular top head, C the bottom head, D the friction cover and F the safety seal, preferably of paper or paste-board. The body A is provided at its upper end with an annular inturned flange a¹ which is embraced by and between the reverse and substantially flat or horizontal folds b b¹ of the rim b² of the inside fitting 70 annular friction top head B. The annular top head B is provided at its inner edge with the customary depending annular friction seat wall b³.

The folded seam uniting the inside fitting annular top B and formed by the can body flange a¹ and flanges or folds b b¹ and rim b² may, if desired, be simply a folded or bump seam, or the seam may be soldered for further tightness and security. The reversely and inwardly folded flanges b b¹ of the rim of the annular top head B forms an annular groove between the upper face b⁴ of said annular top and the lowermost fold b to receive the rim or marginal edge 85 of the safety seal F which is thus securely clamped between said members and firmly held in position so that it cannot be removed without mutilation and cannot be replaced.

The annular top head B with the friction 90 cover D firmly seated therein is first applied to the can body in the form shown in Fig. 5, with the seaming flange a¹ of the can body upright and the flanges b b¹ of the annular top B also upright, the safety seal F is then applied as shown in Fig. 5 and then the flanges a¹, b, b¹ are turned inwardly and bumped down securely upon the safety seal F. If desired, the flanges a, b, b¹ may be partly turned inward before 100 the safety seal F is applied, as indicated by the dotted lines in Fig. 5, as the safety seal may be readily inserted or sprung into position with the flanges a¹ and b b¹ thus partly turned. If it is desired to solder the seam, this is preferably done before the safety seal is applied, especially if the safety seal is made of paper or other like material. After 105 the annular top, friction cover, and safety seal have been applied and firmly secured 110

to the can body, the can is filled, and then the bottom head C is secured to the lower end of the body of the filled can, preferably by a folded or double seam a^2 .

5. The friction cover D has the customary annular friction seat wall d and pry-off rim d^1 furnished with a reinforcing or stiffening flange or fold d^2 . The inturned folded seam formed by the body flange a^1 and 10 annular top head flanges b b^1 serve not only to unite the top head to the can body and as a fulcrum or pry-off rim for levering up the friction cover, but also as the means for securing the external safety seal F across the 15 friction cover and to the can body or its annular top head.

The safety seal F may have printed thereon the trade-mark and name of the party whose coffee, spices or other articles are to 20 be sold in the can.

I claim:

1. In a friction top can, the combination with a can body, of an annular top having a friction seat wall, a friction cover closing 5 the opening in said annular top and having a friction seat wall and a pry-off rim, and an external safety seal of yielding material 10

extending across said cover, said can body and annular top having an inwardly projecting folded seam uniting the same and 30 coöperating as a fulcrum rim with said pry-off rim of the cover and also clamping and securing the safety seal in place, said safety seal being so secured that it is necessarily mutilated when removed, substantially as 35 specified.

2. In a friction top can, the combination with a can body having an inturned flange at its upper end, of an annular top having a friction seat wall and a rim fitting within 40 said can body and provided with reversely folded and inwardly projecting flanges embracing said inturned flange of the can body, a friction cover having a friction seat wall and a pry-off rim, and a safety seal 45 extending across said cover and clamped at its edges between said top head and said in-turned flanges of the rim thereof, substantially as specified.

JOHN M. YOUNG.
